[57] CLAIM

The ornamental design for a dispensing nozzle for container, as shown and described.

DESCRIPTION

FIG. 1 is a top perspective view of a dispensing nozzle for container, showing my new design;

FIG. 2 is a top plan view thereof;

FIG. 3 is a bottom plan view thereof;

FIG. 4 is a side view thereof, the opposite side being a mirror image thereof;

FIG. 5 is a front elevational view thereof; and

FIG. 6 is a rear elevational view thereof.

FIG. 1**FIG. 2****FIG. 3****FIG. 4****FIG. 5****FIG. 6**
